UNITED STATES PATENT OFFICE

JOSEPH VAN ACKEREN, OF PITTSBURGH, PENNSYLVANIA, ASSIGNOR TO THE KOPERS COMPANY, OF PITTSBURGH, PENNSYLVANIA, A CORPORATION OF PENNSYLVANIA

REGENERATIVE HEATING STRUCTURE

Application filed October 5, 1923. Serial No. 666,735.

This invention comprehends improvements in regenerative heating apparatus generally and relates particularly to apparatus that is especially adapted for distilling or coking carbonaceous materials. The invention has for an object the provision of a construction that is thoroughly efficient in operation and which will produce high grade coke, when employed for distilling coal, and effect a substantially complete by-product recovery by a distilling operation conducted with great conservation of heat.

Important characteristics of the invention are the provision of a system of combustion in the flame or combustion flues of the heating walls of the distilling chambers, by which system flame or combustion is maintained concurrently in all of the flues of each heating wall, with periodic reversal in flow of the heating gases and the attainment of efficient combustion and heating effects in each direction of the flow of the heating gases, and with substantially direct connections between a complete reversible regenerative system and both the upper and lower ends of the vertical flame flues, such connections eliminating any necessity for the employment of long vertical gas-flow channels for receiving the entire flow from regenerators feeding up-burning flues, and, instead of such vertical channels, providing for the up-flow combustion in the flues a system of channels and connections between the flues and the regenerators by which the heating gases are distributed for the various flues as soon as the gases leave the regenerators; the construction and arrangement of the regenerative system and connection of the same with the flues in such manner as to attain great efficiency in heating conservation and equality in the distribution of the heating effect in the several distilling chambers of the battery; a ready adaptability for operation with an extraneously derived gas such as producer gas or blast furnace gas, for fuel, with regenerative heating of the fuel gas in some of the regenerators.

In addition to the general objects recited above, the invention has for further objects such other improvements and advantages in

construction and operation as are found to obtain in the structures and devices herein-after described or claimed.

In the accompanying drawings forming a part of this specification and showing, for purposes of exemplification a preferred form and manner in which the invention may be embodied and practiced but without limiting the claimed invention to such illustrative instance or instances:

Figure 1 is a composite vertical sectional and elevational view of a vertical retort construction embodying features above specified and constructed in accordance with the improvements of the present invention, the view being taken on the several vertical planes indicated by the line A—A of Fig. 3;

Fig. 2 is a vertical sectional elevation of the retort construction taken on the several vertical planes indicated by the lines G—G, H—H, and L—L of Fig. 1; and

Fig. 3 is a composite horizontal sectional view taken in the different horizontal planes indicated by the lines B—B, C—C, D—D, and E—E of Fig. 1.

The same characters of reference designate the same parts in each of the several views of the drawings.

In its present embodiment, the invention is incorporated in a vertical retort construction for producing metallurgical coke and one that is especially designed for the employment of an extraneously derived gas, such as producer gas or blast furnace gas for fuel. For convenience, the present description will be confined to this embodiment of the invention; features of construction and operation are, however, capable of other valuable applications, for example, to apparatus generally useful in the heat treatment of materials or to constructions embodying the combination principle exemplified in my co-pending application for Letters Patent of the United States for vertical retort battery, filed February 4, 1921, Serial No. 442,357, Patent No. 1,528,228, issued March 3, 1925; consequently the invention is not confined in its scope to the specific use and embodiment herein described as an illustrative example.

Referring to the drawings, there are illustrated views of a vertical retort battery of the by-product type, as hereinbefore mentioned. The vertical retort battery embodies in its construction a series of distilling chambers, such as the series 11 of vertically elongated retorts or coking chambers, the retorts of such series being contiguous to intermediate heating walls 12 corresponding to the respective series of retorts 11. The heating walls and the retort chambers extend to a great height as compared with their respective widths and the other crosswise dimensions of the retort battery, and the series of retorts with their corresponding intermediate heating walls are, according to the present embodiment of the invention, respectively arranged and extend along one side of the battery assembly, whereas the regenerators extend along the other side of the battery assembly, as will hereinafter appear. The heating walls 12 form the side walls of the respective retorts 11, as shown more particularly in Figs. 2 and 3, and the upper ends of the respective retorts as well as the heating walls are reinforced by side refractory walls designated generally by the reference character 15.

The coal to be coked is charged into the upper end of the retorts 11, and the completed coke is discharged through openings at the bottom of said retorts. Because of the great height of the retorts as compared with their width and crosswise dimensions, the retort battery is preferably employed as a continuous vertical retort. When so employed, a continuous feed of carbonaceous material may be maintained through the retorts 11, with continuous discharge of the finished coke from the bottoms of such retorts. If desired, a suitable form of coke handling and discharging apparatus may be employed for receiving and handling the coke as it drops from the bottoms of said retorts, for example, apparatus such as is shown and described in my prior application for Letters Patent of the United States for regenerative heating structure, filed July 24, 1922, Serial No. 576,985.

The heat for coking the charges of coal in the several retorts 11 is derived from the heating walls 12 corresponding to said retorts. Each heating wall 12 is constituted of a plurality of vertical or combustion flues 37 that are operatively disposed in single groups in their respective heating walls. That is to say, all of the heating flues of each heating wall operate concurrently for flow in the same direction; in fact, the flow is in the same direction during the reversal period throughout the entire system of flues of the battery, as will hereinafter appear.

The regenerators 38 are located on that side of the battery opposite from the retorts 11 and heating walls 12 and are separated from said retorts and heating walls by the medi-

ate wall structure 16. As shown in Fig. 3, the regenerators are located in a single series along one side of the battery, with the major vertical planes of the regenerators parallel to the major vertical planes of the retorts and heating walls. Operatively, the series of regenerators 38 is disposed into two groups R and S, comprising a pair of regenerators, and the regenerators comprising the groups R alternating with the regenerators comprising the groups S. When the several regenerators constituting the group R are operating for inflow, that is to say, for delivering pre-heated gaseous media to the flues of the heating walls, the several regenerators of the other group S are operating for outflow to extract heat from the flue gases discharged into the regenerators from the flues. On reversal of the battery, at the end of each operating period, the inflow regenerators become outflow regenerators and the outflow regenerators become inflow regenerators.

Each regenerator 38 is preferably a high narrow upright chamber containing open brickwork, or checkerwork 40, and having a sole channel 41 underneath and opening up into the checkerwork. The several regenerators are heated by the hot combustion products that are exhausted from the flame or combustion flues hereinbefore mentioned and then, on reversal, impart heat to the medium that they feed to the flues. Whether of the group R, or of the group S, the regenerators are all so connected with appropriate flues, that the inflow always takes place in an upward direction through the regenerators, whereas the outflow is always downwardly through said regenerators.

In the operation of the battery, according to the present embodiment of the invention which employs, preferably, an extraneously derived gas, such as producer gas for fuel, the several regenerators constituting the group R, when in inflow operation, deliver air and fuel gas to the flame flues during the period when the latter are operating for downflow combustion; these regenerators R receive the exhaust gases from the flame flues after reversal, that is to say, during the period when the flame flues are operating for upflow combustion. On the other hand, the several regenerators constituting the group S operate for inflow of air and fuel gas to deliver the same to the flues when the latter are operating for upflow combustion, and the said regenerators S operate for outflow to receive the exhaust gases from the flues during the period when the latter are operating for downflow combustion. This method of operation requires the regenerators R to be connected with the tops of the flame flues 37 and the regenerators S to the bottoms of said flues, the connections for this purpose being a special feature of the invention, as will hereinafter appear.

The several regenerators of each group R and S are constituted of air regenerators A and gas regenerators P, when operating for inflow, and both regenerators of each group are constituted of waste gas regenerators W when operating for outflow. However, the several regenerators R operate for inflow while at the same time the several regenerators S operate for outflow and, on reversal 10 of the flow through the flame flues, the several regenerators S are switched to the inflow function while concurrently the other regenerators R are switched to the outflow function.

15 The several regenerators A of the groups R lead at their upper ends into ducts 53 of which each duct 53 is connected with the upper horizontal flues 55 of a pair of adjacent heating walls. Said horizontal flues 55 are 20 directly connected with the tops of the flame flues in their corresponding heating walls by ports 54. With this construction, each regenerator A of the groups R is directly connected with the upper ends of the flame flues 25 37 of a pair of adjacent heating walls, and all of the flame flues of the battery are thus provided with direct connections with regenerators that supply air to the flues, whenever downflow combustion is maintained in the 30 flues.

The several regenerators P of the groups R lead at their upper ends into ducts 63 of which each duct 63 is connected with the upper horizontal flues 65 of a pair of adjacent 35 heating walls. Said horizontal flues 65 are directly connected with the tops of the flame flues in their corresponding heating walls by ports 64. With this construction, each regenerator P of the groups R is directly connected with the upper ends of the flame flues 40 37 of a pair of adjacent heating walls, and all of the flame flues of the battery are thus provided with direct connections with regenerators that supply fuel gas to the flues, whenever downflow combustion is maintained in the 45 flues.

The several regenerators A of the groups S lead at their upper ends into ducts 73, which respectively connect with horizontal 50 channels 74 located respectively above the flues of a pair of adjacent heating walls. Each horizontal feed channel 74 is connected by ducts 75 with vertical air channels 76, which vertical air channels 76 extend downwardly through the heating wall, respectively between a pair of adjacent flues, with the exception of the air channel located between the extreme inner flue and the regenerator, 55 as shown in Fig. 1. With the exception of said last mentioned channel 76, each air channel is connected by branching ports 77 to the bottom of the pair of flame flues between which it is located. The vertical air channel between the extreme interior flue and the 60 regenerator is connected with that flue by

a single port 78. With this construction, each regenerator A of the groups S is connected by air distributing channels with the lower ends of the flame flues 37 of a pair of adjacent heating walls, and all the flame flues 70 of the battery are thus provided with direct connections with regenerators that supply air to the flues, whenever upflow combustion is maintained in the flues.

The several regenerators P of the groups S lead at their upper ends into ducts 83, which respectively connect with horizontal channels 84 located respectively above the flues of a pair of adjacent heating walls. Each horizontal feed channel 84 is connected by ducts 85 with vertical fuel gas channels 86, which alternate with the vertical air channels 76, as shown in Fig. 1. With the exception of the channel 86 located directly adjacent to the side wall 12 of the structure, each fuel gas channel is connected by branching ports 87 to the bottom of the pair of flame flues between which it is located. The vertical fuel gas channel at the extreme outer part of the structure is connected with the adjacent flue by a single port 88. With this construction, each regenerator P of the groups S is connected by fuel gas distributing channels with the lower ends of the flame flues 37 of a pair of adjacent heating walls, and all the flame 95 flues of the battery are thus provided with direct connections with regenerators that supply fuel gas to the flues, whenever upflow combustion is maintained in the flues.

As shown in Fig. 1 the vertical feed channels of both groups 76 and 86 preferably extend to and through the top and bottom of the structure, providing inspection ports, which may be opened individually for cleaning or other purposes. Normally the inspection ports both at top and bottom are kept closed by plugs or covers. Provision is made for operating the retort structure alternatively with a relatively rich fuel gas such as coke oven gas. For this purpose the tops of the individual flues 37 of each heating wall are provided with coke oven gas feed channels 89, for feeding coke oven gas to the flues during downflow combustion, and the bottoms of said individual flues with individual coke oven gas channels 90 for feeding such gas to the flues during upflow operation of the retort. In coke oven gas operation, the regenerators P of either group R or S are operated for feeding air to the flame flues, 110 through the various channels and ducts hereinbefore described, instead of fuel gas, whether the combustion be up or down through the flame flues.

The operation of the retort battery, assuming that a relatively lean or dilute gas, such as ordinary producer gas, is employed as the fuel in the flues of the heating walls is as follows: If it be assumed that the several regenerators comprising the groups R 120

be operating for inflow and that the flues throughout the battery be operating for downflow combustion, it follows that during this period the regenerators P of the groups R are employed for preheating the fuel gas which is subsequently introduced into the flues. The regenerators A of the groups R are employed for preheating the air to supply the combustion of the gas in the flues. Concurrently all the regenerators of the groups S operate for outflow, or as waste gas regenerators W. The air and fuel gas passes upwardly through the regenerators A and P of the groups R, thence through the ducts 53 and 63 to the horizontal flues 55 and 65 which extend above the tops of the flame flues. From the horizontal flues 55 and 65 the air and fuel gas is directly delivered through the ports 54 and 64 into the tops of the flame flues. Burning downwardly in the flame flues 37, the air and fuel gas discharge at the bottom of said flues as waste gas through the ducts 77 and 78, 87 and 88 into the channels 76 and 86, through which the waste gases rise to the top of the structure. At the top of the channels 76 and 86, the gases pass from said channels through the ducts 75 and 85 into the horizontal channels 74 and 84, which deliver the waste gases to the ducts 73 and 83. In turn, the ducts 73 and 83 feed the waste gases to the tops of the regenerators A and P of the series S. Passing down through said regenerators S the waste gases finally exhaust through the sole channels 41 into the usual waste gas tunnel. Inasmuch as the vertical channels 76 and 86 are directly connected at their tops with the tops of the downflow operating waste gas regenerators, any heat losses that may occur by reason of the counter-current flow between waste gas and downburning flame in the flues of the heating walls, will be communicated directly to the checkerwork in said waste gas regenerators, with the result that such heat loss is again transmitted to the incoming air or fuel gas, when the regenerators S become inflow regenerators after reversal. However, in the structure of this invention, direct heat losses from the flames in the downburning flues are practically negligible, inasmuch as the waste gases from said flues pass directly into the channels 76 and 86 which act at this time as upflow channels. The waste gases themselves have a temperature very little below the temperature in the flues 37, so that the heat differential between the gas in the flues and the waste gas in the channels 76, 86 is very slight. In fact, the heat of the gases in the channels 76, 86 may assist the heat in the flame flues 37 in distilling the carbonaceous material in the adjacent retort.

After reversal, as hereinbefore mentioned, the flame flues 37 are switched to upflow operation and concurrently the regenerators of

the groups S become inflow regenerators and the regenerators of the groups R outflow regenerators. The incoming fuel gas and air rises upwardly through the regenerators of the groups S and passes into the ducts 83 and 73 of the regenerators P and A. From the ducts 83 and 73 at the top of said regenerators, the fuel gas and air passes into the horizontal feed channels 84 and 74 and thence through the feed ducts 85 and 75 into the vertical distributing channels 86 and 76. Passing downwardly through said channels 86 and 76, the fuel gas and air are delivered from the bottom of said channels through the ducts 87, 88 and 77, 78 into the bottoms of the flame flues 37 where ignition of the fuel gas in the air takes place. The waste gases from the upburning flames in the flues 37 pass from the top of said flues through the ports 54 and 64 into the horizontal flues 55 and 65 and thence through the ducts 53 and 63 into the top of the regenerators of the groups R. The waste pass downwardly through said regenerators R and thence out into the exhaust main through the sole channels 41. When upflow combustion is maintained in the flame flues 37, any heat taken from the flame within the flues by the counter-current of air and fuel gas in the channels 76 and 86 is immediately delivered directly back to the flames within the flues, there being a direct recuperative action during upflow combustion in the flues. This recuperative action is attained by the structure of the invention, inasmuch as the fuel gas and the air is distributed for the individual flues as soon as it leaves the top of the inflow regenerators, that is, by the feed channels 86 and 76.

The invention as hereinabove set forth may be variously embodied within the scope of the claims hereinafter made.

I claim:

1. In a vertical retort battery, in combination: a plurality of high narrow retort chambers, each adapted to receive through its top the charge to be coked and adapted to discharge through its bottom the coked charge; heating walls contiguous to such retort chambers and respectively comprising combustion flues alternately operable in unison for upflow and downflow combustion; horizontal flues respectively connected with the tops of the combustion flues; vertical feed channels respectively connected with the bottoms of the combustion flues, said feed channels being located in the heating walls in alternation with the combustion flues; and groups of high narrow regenerators, the regenerators of one group serving the combustion flues for downflow combustion and being directly connected in pairs with the horizontal channels at the top of the combustion flues, and the regenerators of the other group serving the combustion flues for upflow combustion and

being each connected at its top with some of the vertical feed channels, each group of regenerators when operating for inflow comprising both air and fuel gas regenerators.

- 5 2. In a vertical retort battery, in combination: a plurality of high narrow retort chambers, each adapted to receive through its top the charge to be coked and adapted to discharge through its bottom the coked charge; 10 heating walls contiguous to such retort chambers and respectively comprising combustion flues alternately operable in unison for upflow and downflow combustion; horizontal flues respectively connected with the tops of 15 the combustion flues; vertical feed channels respectively connected in pairs with the bottoms of the combustion flues, said feed channels being located in the heating walls in alternation with the combustion flues; and 20 groups of high narrow regenerators, the regenerators of one group serving the combustion flues for downflow combustion and being directly connected in pairs with the horizontal channels at the top of the combustion 25 flues, and the regenerators of the other group serving the combustion flues for upflow combustion and being each connected at its top with some of the vertical feed channels, each group of regenerators when operating for 30 inflow comprising both air and fuel gas regenerators.

3. In a vertical retort battery, in combination: a plurality of high narrow retort chambers, each adapted to receive through its top 35 the charge to be coked and adapted to discharge through its bottom the coked charge; heating walls contiguous to such retort chambers and respectively comprising combustion flues alternately operable in unison for upflow and downflow combustion; horizontal flues respectively connected with the tops of the combustion flues; vertical feed channels respectively connected with the bottoms of the combustion flues, said feed channels being 40 located in the heating walls in alternation with the combustion flues; and groups of high narrow regenerators, the regenerators of one group serving the combustion flues for downflow combustion and being directly connected 45 in pairs with the horizontal channels at the top of the combustion flues, and the regenerators of the other group serving the combustion flues for upflow combustion and being each connected at its top with some of the 50 vertical feed channels, each group of regenerators when operating for inflow being jointly operable for conveying air to the said flues or separately operable for conveying air and an extraneously derived gas.

- 60 4. In a vertical retort battery, in combination: a plurality of retort chambers; heating walls contiguous to such retort chambers and respectively comprising combustion flues alternately operable in unison for upflow and downflow combustion; horizontal flues re-

spectively connected with the tops of the combustion flues; vertical feed channels respectively connected with the bottoms of the combustion flues, said feed channels being located in the heating walls in alternation with the combustion flues; and groups of regenerators, the regenerators of one group serving the combustion flues for downflow combustion and being directly connected in pairs with the horizontal channels at the top of the combustion flues, and the regenerators of the other group serving the combustion flues for upflow combustion and being each connected at its top with some of the vertical feed channels, each group of regenerators when operating for inflow comprising both air and fuel gas regenerators.

5. In a vertical retort battery, in combination: a plurality of retort chambers; heating walls contiguous to such retort chambers and respectively comprising vertical combustion flues alternately operable in unison for upflow and down-flow combustion; vertical feed channels respectively connected with the bottoms of the combustion flues, said feed channels being located in the heating walls in alternation with the combustion flues; and groups of regenerators, the regenerators of one group being connected at their tops directly with the tops of the combustion flues, and the regenerators of the other group being connected at their tops with the vertical feed channels.

6. In a vertical retort battery, in combination: a plurality of retort chambers; heating walls contiguous to such retort chambers and respectively comprising vertical combustion flues alternately operable in unison for upflow and downflow combustion; vertical feed channels respectively connected with the bottoms of the combustion flues, said feed channels being located in the heating walls in alternation with the combustion flues and being composed of fuel gas channels alternating with air channels for feeding both air and fuel gas to each combustion flue; and groups of pairs of regenerators, the regenerators of one group being connected in pairs at their tops directly with the tops of the combustion flues and the individual regenerators of the pairs of the other group being connected the one with the vertical fuel gas feed channels and the other with the vertical air feed channels.

7. A regenerative heating structure, having a plurality of retort chambers with heating walls contiguous thereto and respectively comprising vertical combustion flues alternately operable in unison for upflow and downflow combustion, combined with two groups of regenerators, the regenerators of one group being connected at their tops directly with the tops of the combustion flues, and the regenerators of the other group being connected at their tops with the bottoms of

the combustion flues by duct means alternating with said combustion flues.

8. A regenerative heating structure, having a plurality of retort chambers with heating walls contiguous thereto and respectively comprising vertical combustion flues alternately operable in unison for upflow and downflow combustion, combined with two groups of regenerators, the regenerators of one group being connected directly with the tops of the combustion flues, and the regenerators of the other group being connected with the bottoms of the combustion flues by duct means alternating with said combustion flues.

15 9. In a vertical retort battery, in combination: vertically flued heating walls; retort chambers contiguous thereto; and a regenerative system; the walls being provided with vertical flow channels alternating with the flues said flues and channels communicating with each other at their lower ends, the upper ends of said flues and channels being separately connected with the regenerative system.

20 10. In a vertical retort battery, in combination: heating walls and retort chambers adjacent thereto; a regenerative system on the same level as the heating walls and chambers; the walls being provided with substantially vertical parallel flow channels and vertical flues communicating with each other at their lower ends, said flow channels being located in the heating walls intermediate the vertical flues, the upper ends of said flues and channels being connected with the regenerative system at the top of the latter.

In testimony whereof I have hereunto set my hand.

JOSEPH VAN ACKEREN.
